United States Patent Office.

LEMUEL S. FITHIAN, OF EAST NEW YORK, N. Y., ASSIGNOR TO HIMSELF, JAMES M. HOPKINS, AND JEFFERSON W. SOUTHMAYD, OF NEW YORK CITY.

Letters Patent No. 76,901, dated April 21, 1868.

IMPROVEMENT IN DEVICE FOR MULTIPLYING REVOLUTIONS AROUND AN AXIS.

The Schedule referred to in these Letters Patent and making part of the same.

TO ALL WHOM IT MAY CONCERN:

Be it known that I, LEMUEL S. FITHIAN, of the town of East New York, county of Kings, and State of New York, have invented new and useful Improvements in a Device for Communicating and Multiplying Revolutions Around an Axis; and I do hereby declare the following to be a full, clear, and exact description thereof, which will enable others skilled in the art to make and use the same, reference being had to the accompanying plate of drawings, as forming a part of this specification.

The invention for which I desire to secure Letters Patent consists of a new and novel arrangement of parts, whereby the velocity of rotation on a shaft can be more rapidly increased or decreased, and with greater economy of space and power than with the ordinary combination of cogged wheels.

The device consists of a hollow cylinder, a reversing-wheel, a shaft, a series of multiplying-wheels, and a series of intermediate wheels, with a stand or frame, which supports the shaft.

In the accompanying plate of drawings my improvements are illustrated.

Figure I is a section of the device, taken through the axis of the shaft.

Figure II is an interior view of one end of the cylinder, showing the mechanism of the parts, whereby the cylinder is given a reverse rotation.

Figure III shows the arrangement of the intermediate wheels.

The hollow cylinder, C C, is provided with a partition, c c, near one extremity, by means of which it is held in place on the shaft S S, whose axis is coincident with its axis. The concave or interior surface of the cylinder is cogged on both sides of the partition, the cogs extending parallel with the axis of the cylinder.

A cogged wheel, R, is attached to the axis. The diameter of this wheel is a little less than that of the cylinder, the space between the two being occupied by an intermediate wheel, b, whose cogs mesh with those of R and C, on opposite sides. The direct revolution of the wheel R gives the cylinder a reverse motion, which is equal to the ratio of the interior diameter of the cylinder to the diameter of the reversing-wheel.

On the opposite side of the partition, a lever, L, is attached to the shaft. This lever carries at its outer extremity an intermediate wheel, P, whose cogs mesh with those of the cylinder, and those of a multiplying-wheel, D, the latter turning freely on the shaft S. To the multiplying-wheel D, an arm is attached that carries an intermediate wheel, P'. The cogs of P' mesh with those of the cylinder, and those of the wheel E. A lever or arm of E carries an intermediate wheel, P'', whose cogs mesh with those of a third multiplying-wheel, F, and those of the cylinder.

The intermediate wheels b, P, P', and P'' revolve in straps or clasps, g, and on rivets, whose ends are firmly held or secured by the straps, and for the latter purpose the straps are made to enclose the intermediates.

B is a stand or support, through which the shaft S passes, and which also secures the intermediate wheel b.

From the description given, it must be evident that, if the shaft carrying the reversing-wheel R and the lever L be revolved in either direction, the hollow cylinder C C will be made to revolve in the opposite direction with a velocity which will bear the ratio to the velocity of the shaft of the cogged diameter of the reversing-wheel R to the interior diameter of C, and that the wheel D will revolve with a velocity due to the direct velocity of L, the reverse velocity of C, and the ratio of the diameter of the wheel D to the interior diameter of the cylinder C.

In the drawings herewith submitted, the diameter of the wheel R is one-half of that of the cylinder C, and therefore, for each direct revolution of the shaft, the cylinder will make one-half of a revolution in the opposite direction. The diameters of the multiplying-wheels D, E, and F are one-half of the diameter of the cylinder. The wheel D revolves four times, the wheel E thirteen times, and the wheel F forty times, for each revolution of the shaft. By comparing these numbers, the law of increase of velocity of rotation will be evident, viz, the velocity of any wheel is equal to unity increased by three times the velocity of the multiplying-wheel next preceding.

By increasing the ratio of the interior diameter of the cylinder to the diameter of the reversing-wheel R,

the reverse motion of B will be correspondingly increased, as also the direct motion of D, E, and F. The cylinder C may be given a reverse velocity greater than the direct velocity of the shaft, by so arranging the intermediate, b, that it shall mesh with a circle of cogs on the wheel R, larger than the circle of cogs on C, with which it meshes. This may be done in any one of several obvious ways.

By increasing the ratio of the diameter of the cylinder to the diameters of the multiplying-wheels D, E, and F, a further increase of velocity may be obtained without increasing the number of wheels.

I do not intend to limit myself to the ratios herein given, nor to the number of wheels explained above.

I claim as new, and desire to secure by Letters Patent, as follows, viz:

1. I claim the combination of the reversing-wheel R, partitioned, revolving cylinder C, with one or more sets of multiplying and intermediate wheels, D and P, with straps, g g, when combined substantially as herein set forth.

2. I claim the straps g, g, g, and g, and their equivalents, when employed to sustain and strengthen the ends of the axes on which the intermediate wheels P, P', and P'' revolve.

3. I claim the reversible hollow cylinder C, by means of one or more wheels, R and b, one having an axis coincident with the axis of the shaft, and the other or others parallel therewith.

LEM'L S. FITHIAN.
